UNITED STATES PATENT OFFICE

AZEL AMES, JR., OF CLEVELAND, OHIO, AND JOHN S. HOBSON, OF EDGEWOOD PARK, PENNSYLVANIA, ASSIGNORS TO THE UNION SWITCH AND SIGNAL COMPANY, OF SWISSVALE, PENNSYLVANIA, A CORPORATION OF PENNSYLVANIA.

RAILWAY SIGNALING SYSTEM.

No. 821,916.

Specification of Letters Patent.

Patented May 29, 1906.

Application filed February 24, 1906. Serial No. 302,751.

To all whom it may concern:

Be it known that we, AZEL AMES, JR., residing at Cleveland, in the county of Cuyahoga and State of Ohio, and JOHN S. HOBSON, residing at Edgewood Park, in the county of Allegheny and State of Pennsylvania, citizens of the United States, have invented certain new and useful Improvements in Railway Signaling Systems, of which the following is a specification.

Our invention relates to railway block-signaling systems in which the railway-signals comprised in the system are automatically controlled by a car or train traveling along the railway, and particularly relates to systems wherein the indications given by the signals embrace not only the condition of the block lying immediately ahead, but embraces also an indication of the condition of the next succeeding block. Such indications are usually given by using two arms, (usually upon the same post,) the upper for the block ahead and the lower for the next succeeding block; but they are not unfrequently given by a single blade having three positions of indication. Usually the mechanism designed to operate two separate home and distant signals on the same post is adaptable to give the desired movements to one arm having three positions of indication. Such a railway-signal is shown and described in Patent No. 638,478, and the controlling circuits and appliances used for the one system are hence equally applicable to the other. The indications commonly ascribed to the positions of the semaphore-arms in a two-position home and distant system are as follows: Home signal in horizontal position indicates "danger—stop." Home signal in inclined position indicates "clear—proceed." Distant signal in horizontal position indicates "caution—proceed." Distant signal in inclined position indicates "clear—proceed." In the single-arm railway-signal having three positions of indication the indications are as follows: Horizontal indicates "danger—stop." Inclined at forty-five degrees above or below horizontal indicates "caution." Inclined at ninety degrees above or below horizontal indicates "clear—proceed." In the following description we have usually referred to the indications given by the

signals as horizontal for "danger" or "caution," and inclined for "clear."

We will describe a railway signaling system embodying our invention and then point out the novel features thereof in claims. We have preferred to illustrate and describe a two-arm home and distant system, though the circuits and apparatus as hereinafter set forth and described are equally applicable to the single-arm three-position system.

In the accompanying drawings, Figures 1, 2, 3, and 4 illustrate, respectively, diagrammatic views of a portion of a railway and a signaling system embodying our invention applied thereto, the several figures showing the normal condition of the signals and their controlling-circuits and also the condition of said signals and circuits as they are affected by a car or train in passing along and through the several block-sections. Fig. 5 is a diagrammatic view showing a car or train entering the main line from a siding or branch and the effect such car or train will have on the circuits and associated signals. Fig. 6 is a similar view illustrating a system embodying our invention, wherein certain relays, circuits, and contacts are omitted.

Similar reference characters designate corresponding parts in all the several figures of the drawings.

A designates a portion of railway-track, and *a a'* insulations provided at different points in the railway-track in the usual manner for dividing it into a number of blocks or sections *A' A² A³*, &c. At the entrance end of each block-section a railway-signal *S S' S²*, &c., is provided, and these signals may be of any desired or usual construction, although those of the semaphore type are preferably employed, and this type of signal we have diagrammatically illustrated in the drawings. Each railway-signal is shown as provided with two semaphore-blades *s s' s² s³ s⁴ s⁵*, &c., *s s² s⁴*, &c., being the "home" semaphores and *s' s³ s⁵* being the "distant" semaphores, although, if preferred, each railway-signal may be provided with one semaphore-arm capable of displaying three distinct indications, as hereinbefore described. The railway-signals are primarily controlled by track-circuits, one being provided for each block-section, and the passage of a train

through the block-sections successively affects these and other circuits to cause or permit the railway-signals to operate. For example, a train or car entering and passing along block-section A' will effect the track-circuit thereof, and railway-signal S will be operated to permit its semaphores to move to their horizontal positions, and after the train or car has passed out of block-section A' and into block-section A² the home semaphore on the railway-signal S (for block-section A') will be moved to its inclined or clear position, while the distant semaphore on the same railway-signal will be held in its horizontal or caution position. When the train shall have passed into the block-section A³, the circuits for the railway-signal S will again be affected to cause the distant signal thereof to be moved to the inclined position. The train also on entering block-section A² affects the track-circuit thereof to permit the semaphores of railway-signal S' (designated s², s³) to move to their horizontal positions, and so on throughout the entire system. This, however, is well known in the art and needs no further description.

In Figs. 1 to 5 we have shown block-sections A', A², A³, &c., as being subdivided to form what is termed in the art as "cut" sections by providing intermediately-disposed insulations a², a³, in which event additional track-batteries B', B³, B⁵, &c., will be provided for each of the subdivided sections. These cut sections may be provided where the block-sections are unusually long and in other cases which would render a single battery insufficient for providing the necessary energy to operate the relay or relays of the block-section. In Fig. 6 the block-sections are shown as not being divided. So far as our invention is concerned either arrangement may be employed.

As hereinbefore stated, each block-section is provided with a track-circuit, each of which may be traced as follows, Figs. 1 to 5: starting from one pole of battery B to wire 2, rail 3, wire 4 to and through relay R, wire 5, opposite rail 6, and wire 7 to battery B. The armature r of relay R when attracted to its front contact closes a second circuit which, starting from one pole of battery B', is wire 8, rail 9, wire 10, relay R', wire 11, opposite rail 12, wires 13 14 15, armature r' of relay R, and wire 16, back to battery B'. The armatures r r' r² r³ r⁴ of the relays R R' R² R³ R⁴ are included in "line-circuits." The relays R R', &c., may be of a well-known construction and are, with their armatures, diagrammatically illustrated to show the different circuits in which they are included.

B⁶, B⁷, B⁸, &c., designate what we term "main" batteries or any desired sources of electric energy, one pole of each being connected with a common line-wire L, while the other poles are included in line-circuits, as

will hereinafter appear. In our invention a battery B⁶, &c., is used for operating a railway-signal for a block-section and controlling a railway-signal for an adjacent block-section. In the case of battery B⁷ it is intended for the operation of railway-signal S' and for the control of railway-signal S, in its rear. In the case of battery B⁸ it is intended for the operation of railway-signal S² and for the control of railway-signal S'. 75

Relays R⁶ R⁷ R⁸ R⁹ R¹⁰ R¹¹, &c., are provided for and are included in what we herein term the "line-circuits" and control the operation of the railway-signals, and we shall hereinafter refer to them as "line-relays." 8c These line-relays are arranged in pairs, one pair being provided for each railway-signal and preferably so wound that one relay in each set not only has a greater ohmic resistance than the other, but is in itself made "slow 85 releasing." By "slow - releasing" we wish to be understood as meaning that the relay acts to release or drop its armature slowly and will not release its armature when the current passing through its coils is momentarily interrupted. Such types of relays are well known in the art and usually comprise a closed circuit which acts to retard the demagnetization of the core of the relay when the energizing-current is cut off from the relay. The coils of the other relays R⁶ R⁸ R¹⁰, &c., in each set are wound to a lower ohmic resistance than those of the slow-releasing relays R⁷ R⁹ R¹¹, &c., so that under certain conditions—namely, when the amount of current flowing through these coils is less than a certain amount, due to the presence of a resistance-coil in the circuit or other causes—they will not be sufficiently energized to attract their armatures r⁶ r⁸ r¹⁰, &c. The coils 100 of the line-relays R⁷ R⁹ R¹¹, &c., are wound to higher ohmic resistance than the coils of the line-relays R⁶ R⁸ R¹⁰, &c., and for purposes of illustration let it be assumed that each of the line-relays R⁶ R⁸ R¹⁰, &c., are 110 wound to a resistance of seventy-five ohms and each of the slow-releasing line-relays R⁷ R⁹ R¹¹, &c., are wound to a resistance of three hundred ohms. In order to control the opening and closing of the relays R⁶ R⁷ R⁸ R⁹ R¹⁰, &c., under certain conditions, we may employ resistance-coils and circuit-controllers. 115

O O', &c., designate resistance-coils of, say, seven hundred ohms each, which are included at times in the circuits of the line-relays R⁶ R⁷ R⁸, &c. Appropriate circuit-controllers C¹ C² C³, &c., operated, preferably, by the semaphores, are employed at times to cut in and out of the line-circuits the resistances O O', &c., and circuit-controllers C² C⁴ C⁶, &c., 125 also operated, preferably, by semaphores, are employed to momentarily open the line-circuits. By means of these circuit-controllers the resistance in the line-circuits of the line-relays R⁶ R⁷ R⁸ R⁹ R¹⁰ R¹¹, &c., may be va- 130

ried, and different line-relays may be caused to respond at different times to the current flowing through the line-circuits.

The circuit-controllers $C' C^2 C^3 C^4 C^5$, &c., may be of any ordinary or usual construction; but it is preferable that the controllers $C^2 C^4$, &c., should be quick-acting in order that only a momentary break in the circuits in which they are included may take place 10 while the signal-arm (preferably the home-signal arm) is moving from one of its positions of indication to another. This is for the purpose of momentarily cutting out the main batteries $B^6 B^7 B^8$, &c., from the line-relays $R^6 R^7 R^8 R^9 R^{10} R^{11}$, &c., so as to insure the positive release of the armatures of relays $R^6 R^8 R^{10}$, &c., where such release is required, as will be later on described.

Referring particularly to Fig. 1, the circuits for controlling the operation of the railway-signals from batteries $B^6 B^7 B^8$ may be traced as follows: starting from battery B^7 , thence through wires 17 18, circuit-controllers $C^2 C'$ of railway-signal S' , wire 19, armature and front contact of track-relay R' , wire 20, armature and front contact of relay R , wire 21, line-relays $R^7 R^9$, wire 22, common wire L and wire 23, back to battery B^7 . When the circuit-controllers $C^2 C'$ are opened, the line-circuit is closed at that point through wire 24^a and resistance O . Such controlling-circuits, as above described, are provided for each railway-signal.

The operation of local circuit for each railway-signal may be traced as follows: For example, railway-signal S' . The circuit for the home semaphore s^2 of this railway-signal is battery B^7 , wires 17 24 25, operating mechanism for semaphore s^2 , wire 26, armature 40 and front contact of relay R^9 and wires 27, L , and 23 to battery B^7 . The circuit for the distant semaphore s^3 of this railway-signal is battery B^7 , wires 17 24 28, operating mechanism for distant semaphore s^3 , wire 29, circuit-breaker C , operated by home semaphore S , wire 30, armature and front contact of relay R^8 , and wires 27, L , and 23, to battery B^7 . Such operating-circuits as above described are provided for each railway-signal. 50 Fig. 1 designates the usual condition of the circuits, apparatus, railway-signals, &c.; in short, the system and the railway-signals when no car or train is present. In this condition the resistances $O O'$, &c., are shunted, 55 so that the full currents from the batteries $B^6 B^7$, &c., are flowing through the line-circuits and line-relays. Currents from the batteries $B^6 B^7$, &c., are flowing in the operating or local circuits of the railway-signals, and they 60 are consequently in their inclined or clear position of indication.

Referring now to Fig. 2, it will be noted that a train or car is in the block-section A' , which will have the effect of short-circuiting 65 the battery B , causing the track-relays $R R'$

to drop their armatures. When this occurs, the line-circuit on line-relays $R^6 R^7$ is opened and the relays drop their armatures, thus opening the operating or local circuits on railway-signal S , thereby permitting the 70 semaphores $s s'$ thereof to move to their horizontal positions. The train or car on passing from the block-section A' into the block-section A^2 (see Fig. 3) causes the short-circuiting of the relays $R^2 R^3$, which drop their armatures and open the line-circuit on line-relays $R^8 R^9$, which in turn drop their armatures and open the operating or local circuits of railway-signal S' , thereby permitting the 80 semaphores $s^2 s^3$ thereof to move to their horizontal positions. As soon as the train passes out of the block-section A' the track-relays $R R'$ again attract their armatures and close the line-circuit on relays $R^6 R^7$. The movement of the semaphore s^2 of railway-signal S' to the horizontal position opens the circuit-controller C' and momentarily opens circuit-controller C^2 , so that the current for line-circuit for relays $R^6 R^7$ passes through resistance O . The current flowing 90 through the line-circuit at this time is sufficient only to cause line-relay R^7 to pick up its armature, and thus close the operating or local circuit of semaphore s of railway-signal S , (see Fig. 3,) which will cause semaphore s 95 to move to its inclined position, thus closing the circuit-controller C , located at that point.

When the train leaves block-section A^2 and enters block-section A^3 , (see Fig. 4,) railway-signal S^2 is affected in the same manner as 100 described in connection with railway-signals $S S'$. The moving of the home semaphore s^2 of railway-signal S' to its inclined position operates the circuit-controller C' located at that point to cut out the resistance O , so that 105 current from battery B^7 will be sufficient to energize both line-relays $R^6 R^7$ and cause them to attract their armatures and close the operating or local circuits of railway-signal S .

In Fig. 6 precisely the same arrangement 110 of circuits, relays, and other apparatus is shown as in Figs. 1 to 4, the only difference being that the block-sections $A' A^2$, &c., are not cut, as in Figs. 1 to 4. This arrangement, Fig. 6, eliminates a relay and battery cell 115 from the track-circuit of each block-section. The system of Fig. 6 operates in precisely the same manner as described in connection with Figs. 1 to 4.

An advantage of employing quick-acting 120 circuit-breakers—to wit, $C^2 C^4 C^6$, &c., and slow-acting relays $R^7 R^9$, &c.—will now be pointed out. Should the home signal of a block-section by any chance momentarily be set to its horizontal position in a manner different from the hereinbefore-described regular operation of the system—as, for example, by a train backing into a block-section or entering a block-section from a siding, (see Fig. 5,) or should any other condition arise to 125

set such home signal to its horizontal position, the opening of a circuit-breaker $C' C^3$, &c., as the case may be, would, of course, cut in a resistance-coil $O O'$, &c.; but this action of the circuit-breaker $C' C^3$, &c., might not sufficiently reduce the current flowing through the coils of the relays $R^6 R^8 R^{10}$, &c., to release their armatures $r^6 r^8 r^{10}$, &c. The movement, however, of the quick-acting circuit-controllers $C^2 C^4$, &c., will positively open the circuits controlling the relays $R^6 R^7 R^8 R^9 R^{10} R^{11}$, &c., momentarily while the home signal is traveling between the horizontal and inclined positions, and vice versa, but will close them before reaching either extreme position. An object of constructing the relays $R^7 R^9 R^{11}$, &c., so as to be slow releasing is that their armatures $r^7 r^9 r^{11}$, &c., may not be effected by the momentary opening of the controlling-circuits. On the other hand, the relays $R^6 R^8 R^{10}$, &c., as the case may be, will be deenergized, permitting their armatures to drop and open the circuits on the semaphores controlled by them, so as to permit the semaphores to move to the horizontal position. This advantage is illustrated in Fig. 5, where we have shown a train or car T as entering the block-section A^2 from a siding T' . Under these conditions both semaphores of the railway-signal S' are in the horizontal position, as is also the distant semaphore s' of the railway-signal S . It will be seen, therefore, that in the control of a home and distant signal or their equivalent three-position signal but two line-wires are used instead of three, as heretofore, and that the individual control of a home or distant signal or their equivalent three-position signal is obtained by varying the resistance in the line-circuits for the signals.

Having thus described our invention, what we claim is—

1. In a block-signaling system, the combination of a home semaphore and a distant semaphore located at the entrance end of each block-section, a relay of one resistance for controlling a home signal, and a relay of a different resistance for controlling a distant signal, a line-circuit and battery for each pair of relays, a resistance, and means for cutting said resistance into and out of said line-circuit, the operation being such that when the resistance is in circuit with the relays only one of such relays will be energized by the battery in such circuit to attract its armature but when the resistance is cut out of the circuit both of the relays will be energized by current from the battery in such circuit to attract their armatures.

2. In a block-signaling system, the combination with a signal device having a plurality of positions of indication, located at the entrance end of a block-section, a relay of one resistance for controlling the indication of the signaling device for one block, and a relay of

a different resistance for controlling the indication of the signaling device for another block, both relays being located at the same point, a line-circuit and battery for each pair of relays, a resistance, and means for cutting said resistance into and out of said line-circuit, the operation being such that when the resistance is in circuit with the relays only one of such relays will be energized by the battery in such circuit to attract its armature but when the resistance is cut out of the circuit both of the relays will be energized by current from the battery in such circuit to attract their armatures.

3. In a block-signaling system, the combination of a home semaphore and a distant semaphore located at the entrance end of each block-section, a relay of one resistance for controlling a home signal, and a relay of a different resistance for controlling a distant signal, both relays being located at the same point, a line-circuit and battery for each pair of relays, a resistance, and means operated by a home signal of a different block-section for cutting said resistance into and out of said line-circuit, the operation being such that when the resistance is in circuit with the relays only one of such relays will be energized by the battery in such circuit to attract its armature but when the resistance is cut out of the circuit both of the relays will be energized by current from the battery in such circuit to attract their armatures.

4. In a block-signaling system, the combination of a home semaphore and a distant semaphore located at the entrance end of each block-section, a relay of one resistance for controlling a home signal, and a relay of a different resistance for controlling a distant signal, both relays being located at the same point, a line-circuit and battery for each pair of relays, a resistance, and a circuit-controller operated by a home signal of a different block-section for cutting said resistance into and out of said line-circuit, the operation being such that when the resistance is in circuit with the relays only one of such relays will be energized by the battery in such circuit to attract its armature but when the resistance is cut out of the circuit both of the relays will be energized by current from the battery in such circuit to attract their armatures.

5. In a block-signaling system, the combination of a home semaphore and a distant semaphore located at the entrance end of each block-section, a relay of one resistance for controlling a home signal, and a relay of a different resistance for controlling a distant signal, both relays being located at the same point, a line-circuit and battery for each pair of relays, a resistance, and a circuit-controller operated by a home signal of a different block-section for cutting said resistance into and out of said line-circuit, the operation being such that when the resistance is in circuit with the relays

only one of such relays will be energized by the battery in such circuit to attract its armature but when the resistance is cut out of the circuit both of the relays will be energized by current from the battery in such circuit to attract their armatures.

6. In a block-signaling system, the combination of a home semaphore and a distant semaphore located at the entrance end of each block-section, a relay of one resistance and slow acting for controlling a home signal, and a relay of a different resistance for controlling a distant signal, both relays being located at the same point, a line-circuit and battery for each pair of relays, a resistance, and a circuit-controller operated by a home signal, of a different block-section for cutting said resistance into and out of said line-circuit, the operation being such that when the resistance is in circuit with the relays only one of such relays will be energized by the battery in such circuit to attract its armature but when the resistance is cut out of the circuit both of the relays will be energized by current from the battery in such circuit to attract their armatures.

7. In a block-signaling system, the combination of a home and distant semaphore for each block-section, a relay for each home and each distant semaphore included in series with a battery in the same line-circuit, a resistance, and train-controlled means for cutting said resistance into and out of the line-circuit.

8. In a block-signaling system, the combination of a home and distant semaphore for each block-section, a relay for each home and distant semaphore included in series with a battery in the same line-circuit, and train-controlled means for varying the resistance in said line-circuit whereby one or both of said relays may be made to respond to close the circuit on its semaphore.

9. In a block-signaling system, the combination of a home and distant semaphore for each block-section, a relay for each home and each distant semaphore included in series with a battery in the same line-circuit, a resistance and means operated from a second home signal for cutting said resistance into and out of the line-circuit of the two relays, the operation being that when the resistance is in the line-circuit only one of the relays will respond to the current of the battery, but when cut out of the circuit both relays will respond to the current of the battery.

In testimony whereof we have signed our names to this specification each in the presence of two subscribed witnesses.
